CLAIM

The ornamental design for an angled tower bicycle parking stand, as shown and described.

DESCRIPTION

FIG. 1 is a perspective view of an angled tower bicycle parking stand;

FIG. 2 is a front elevation view of the invention;

FIG. 3 is a rear elevation view of the invention;

FIG. 4 is a right side elevation view of the invention;

FIG. 5 is a left side elevation view of the invention;

FIG. 6 is a top plan view of the invention;

FIG. 7 is a bottom plan view of the invention; and,

FIG. 8 is a perspective view of the invention in use with a bicycle parked adjacent thereto.

The broken lines in the drawings represent unclaimed environmental subject matter and form no part of the claim.
